J. D. BUNDY

RAILWAY CROSSING

Filed July 16, 1927

INVENTOR

J. D. Bundy.

BY *Mann & Co.*
ATTORNEY

UNITED STATES PATENT OFFICE.

JEHU DARLING BUNDY, OF DE KALB, TEXAS.

RAILWAY CROSSING.

Application filed July 16, 1927. Serial No. 206,349.

This invention relates to railway crossings, the main object thereof being to provide means for positively preventing persons unknowingly driving upon a railway track as is often done, causing serious injury and loss of life unless some definite barrier is in the path of travel of the vehicle.

The ordinary signals are sometimes hidden from view of the driver and are often entirely ignored until he is practically upon the railway track.

My invention contemplates a permanent or temporary barrier of obstruction that will compel a driver to detour then stop at railroad track to readjust engine control, then back through restricted passage shown in diagram, again stop to readjust his engine before proceeding on highway. These stops are to enable him to see approaching trains.

A further object of the device is to provide means that will prevent a driver taking an absolutely straight path across a railway crossing.

A further object is to provide means whereby wagons are provided with an auxiliary passage across a railway crossing.

A further object is to provide for a safety railway crossing where the main highway is disposed angularly with respect to the railway track crossing, and indeed even where the main highway extends parallel with the railway crossing.

A further object is to provide means whereby a driver will be compelled to stop at railway tracks, thereby providing an opportunity to see approaching trains.

A further object is to provide a gate across the main highway that while permanently locked by keys in possession of highway official against ordinary traffic, is wide enough when open to permit passage of highway equipment.

With these and other objects in view my invention in certain details of construction, arrangement of parts and combinations of elements as will be hereinafter described and pointed out in the drawings forming a part hereof, and in which:

Figure 1 is a plan view showing a form of the invention wherein a highway or roadway is arranged to cross a railway crossing at right angles.

Figure 2 is a similar view showing an arrangement where the highway runs generally parallel with the railway track.

In carrying out my invention which may be used with either single or double track railways, 1 designates the railway crossing and 2 the main highway; the highway is enlarged laterally as at 3 on opposite sides of the railway, the enlargements being reversely arranged on opposite sides of the railway so that these enlargements 3 are diagonally disposed with respect to each other and constitute pockets within which the automobile must enter. These pockets are defined by right angular picket fences reversely arranged and facing each other, and by picket fences 5 disposed alongside the railway track. On the opposite side of the track barb wire fence may be disposed to prevent encroachment of stock upon the tracks.

By the arrangement of fences above mentioned it will be observed that a driver approaching from the highway will be compelled to slow down and to turn to the left into the branch road and stop at the fence at the railway track to readjust his engine control to back through a restricted passage, again stop to readjust engine to regain highway and cross the railway crossing. These stops so enable him to see approaching train.

A small gate 6 is provided for wagons in the fence adjacent the railway tracks. This gate is for farm wagons and must be opened by the driver thereof.

The first angular fence is extended across the road as at 7 and is provided with a large gate 8 that is permanently locked, the keys being in possession of the highway authorities; this gate 8 however is wide enough to permit passage of highway equipment when necessary and is then locked again, so that it practically forms a constant barrier across the highway, causing an approaching driver to slow down and detour into the road enlargement or pocket.

The arrangement of fence sections on the other side of the railway is practically the same except there need to be no duplicate smaller road for farm wagons, the road 9 and gates 6 and 10 being usually ample for this purpose.

Where the highway runs parallel with the railway crossing the arrangement is as shown in Figure 2, the installation of the main elements of the device being practically the same.

From an inspection of Figure 1 it will be seen that the driver coming along the road from the left in direction of the arrows will be forced to turn to the left due to the barrier gate 8 being in the way, and will slow down, turning into space or pocket 3 and doubling back passes between the angular fence corners or mazes and then out onto the highway and thence over the railway crossing and into the enlargement or pocket on the other side, and out again onto the highway.

It will be observed that the driver on his approach can see to the right whether a train is approaching from that direction, and when he gets into the pocket or enlargement 3 he can observe to the left for the same manifestation.

With the driver coming from the opposite directions the conditions will be just the reverse.

The auxiliary wagon road 9 is guarded by gates 6 and 10 on either side of the railway, and the driver must leave the wagon to open these gates, thus presenting an additional element of safety; these gates are just wide enough to permit a farm wagon to pass through.

It will be apparent from the foregoing that liability of accidents in driving over railway crossings will be minimized by my invention if not entirely eliminated.

The apparatus may also be used as a single unit in a roadway, for preventing speeding and is not restricted to its use in connection with a railway crossing.

It is to be understood that the form of the invention herewith shown and described is to be taken as a preferred embodiment of the same, and that various changes in the shape, size and arrangement of parts may be resorted to without departing from the spirit of the invention or the scope of the appended claims.

Having thus described my invention, what is claimed is:

1. A railroad crossing having in the roadway adjacent the track a permanent barrier extending entirely across the roadway on opposite sides of the crossing and means deflected laterally of the roadway whereby to cause a detour and stopping at railroad track, backing and again stopping of the vehicle before entrance again to the roadway.

2. A railroad crossing comprising a roadway crossing the railway at an angle, said road being provided with an enlargement or pocket having a series of oppositely facing angular fence sections whereby to cause

an approaching car to double back before final entrance of the roadway.

3. The combination with a railway crossing, of a main roadway intersecting the same, pairs of laterally offset pockets, containing oppositely facing angular fence sections therein and a branch restricted passage between said fence sections, whereby to cause an approaching vehicle to back to pass through the branch restricted passages before entering the main roadway.

4. The combination with a railway crossing, of a main roadway intersecting the same, a permanent barrier extending completely across the roadway at or near the railway crossing, and lateral pockets or enlargements in advance of said barriers, said enlargements having therein angular fence sections oppositely facing each other to provide a branch passage of a restricted nature, whereby to cause a vehicle to stop and readjust running control before entering the main roadway beyond the said barriers.

5. The combination with a railway crossing, of a main roadway intersecting the same, a permanent barrier extending completely across the roadway at or near the railway crossing, said roadway having lateral enlargements or pockets on opposite sides of the tracks and in diagonal relation to each other, and a branch road for smaller vehicles leading from one of said pockets and intersecting the railway laterally of the intersection of the main roadway, said branch road then merging with the main roadway beyond the said barrier.

6. The combination with a railway crossing, of a main roadway intersecting the same, barriers extending entirely across the main roadway and beyond one side thereof, said barriers being disposed on opposite sides of the crossing, the barriers each provided with a gate permanently locked, the roadway expanded laterally adjacent said barriers to form pockets and labyrinthine obstructions in said pockets, whereby to cause a driver to enter said pockets and double back before reentering the main roadway and crossing the railway.

7. An obstruction device for a roadway, comprising a permanent barrier extending entirely across and laterally beyond both sides thereof, a lateral enlargement or pocket adjacent one side extension, and restricted passages within said pocket, whereby to cause a driver to stop and readjust engine control to pass through the restricted passages.

JEHU D. BUNDY.
